Primary Examiner — Marie D. Fast Horse*Assistant Examiner* — Josiah D. Parsons(74) *Attorney, Agent, or Firm* — Locke Lord LLP; Tim Tingkang Xia, Esq.(57) **CLAIM**

The ornamental design for a “keyboard dock,” as shown and described.

DESCRIPTION

FIG. 1 is a top, front and right-side perspective view of a keyboard dock showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a top, front and right-side perspective reference view of the keyboard dock of FIG. 1, shown in a state of use with an environmental keyboard;

FIG. 9 is a top, rear and left-side perspective reference view thereof;

FIG. 10 is an enlarged view of portion 10 in FIG. 8; and, FIG. 11 is an enlarged view of portion 11 in FIG. 9.

The dot-dash broken lines seen in the drawings represent the boundary of the enlarged portions and form no part of the claimed design. The broken lines showing the additional keyboard in FIGS. 8 and 9 depict unclaimed environmental subject matter only and form no part of the claimed design. All other broken lines seen in the drawings depict portions of the keyboard dock that form no part of the claimed design.
